No. 36,675.

Patented December 8, 1903.

UNITED STATES PATENT OFFICE.

JOHN EHRENPREIS, OF CHICAGO, ILLINOIS, ASSIGNOR TO THE BRUNSWICK-BALKE-COLLENDER COMPANY, OF CHICAGO, ILLINOIS, A CORPORATION OF OHIO.

DESIGN FOR A BACK-BAR FIXTURE.

SPECIFICATION forming part of Design No. 36,675, dated December 8, 1903.

Application filed September 24, 1903. Serial No. 174,525. Term of patent 14 years.

To all whom it may concern:

Be it known that I, JOHN EHRENPREIS, a citizen of the United States, residing at Chicago, in the county of Cook and State of Illinois, have invented a new, original, and ornamental Design for a Back-Bar Fixture, of which the following is a specification, reference being had to the accompanying drawing, forming part thereof.

10 In the accompanying drawing I have shown my new design of back-bar in perspective.

What I claim as my invention, and desire to secure by Letters Patent, is—

The ornamental design for a back-bar fixture, as shown.

JOHN EHRENPREIS.
